UNITED STATES PATENT OFFICE.

JOHN MUTH, OF NORWALK, CONNECTICUT, ASSIGNOR TO THE E. H. HOTCHKISS COMPANY, OF NORWALK, CONNECTICUT, A CORPORATION OF CONNECTICUT.

STAPLE-DRIVING MACHINE.

Application filed March 24, 1921. Serial No. 455,122.

To all whom it may concern:

Be it known that I, JOHN MUTH, a citizen of the United States, residing at Norwalk, county of Fairfield, State of Connecticut, have invented an Improvement in Staple-Driving Machines, of which the following is a specification.

This invention relates to stapling machines, and more particularly to that type known as strip staple machines, wherein each staple, at the time it is driven, is severed from a strip of integrally connected staples which is fed forwardly at each operation of the machine to bring the staples successively into a position to be severed and driven.

The invention has for its object the provision of improved means for rigidly holding each staple, as it is severed from the strip, in such a position as to cause it to be cut off squarely and for positively guiding and carrying the severed staple through the throat of the machine, thereby effectually overcoming the difficulty frequently encountered in the use of machines of this type due to the tendency of the cutting and driving mechanism, particularly when said mechanism has become slightly dull, to bend the staples instead of severing them cleanly, and to the occasional tendency on the part of the staples themselves, from the foregoing or other causes, to turn in the throat and to become wedged therein or to be driven into the work at an inclination instead of being driven straight through the throat in the proper manner.

With the foregoing and other objects in view, I have devised the novel stapling mechanism which I will now describe, reference being had to the accompanying drawing forming a part of this specification, and in which:

Fig. 1 is a longitudinal vertical section of the complete machine, showing the interior parts in elevation.

Fig. 2 is a detail vertical section on the line 2—2, Fig. 1, with the plunger removed.

Fig. 3 is a detail section on the line 3—3, Fig. 2.

Fig. 4 is a detail perspective view, on an enlarged scale, of one of the staple holding and carrying members.

Figs. 5 and 6 are fragmentary detail views, on an enlarged scale, of the front end of the staple strip carrying bar and the

lower end of the plunger, illustrating different steps in the operation.

Fig. 7 is a detail sectional view on the line 7—7 Fig. 6.

Fig. 8 is a fragmentary perspective view, 60 on a still further enlarged scale, of a portion of the plunger and a portion of one of the staple holding and guiding members associated therewith.

Fig. 9 is a perspective view of a pair of 65 staple holding and carrying members, illustrating a modification.

10 denotes the machine base, which is provided at its forward end with an anvil 11 having the usual clenching recess 12. 70 Pivoted to said base is the head of the machine, which comprises a casing 13 open at the bottom and having the lower edges of its side walls secured, as by pins 14, to a staple strip carrying bar 15 upon which 75 the staple strip slides, said bar being pivoted at 16 between upstanding ears 17 at the rear end of the base 10. The upper portion of the bar 15 is spaced from the side walls of the casing 13 by plates 18 interposed between said bar and walls in order to provide the necessary clearance for the free passage of the staple strip 19. At 80 its forward end the casing 13 is formed with a vertically disposed, substantially 85 cylindrical guide 20 for a vertically reciprocating plunger 21 having oppositely disposed longitudinal ribs 22 which are received in oppositely disposed vertical grooves 23 (see Figs. 2 and 3) in the guide 90 20. The plunger 21 is provided with a knob or hand piece 24 between which and the top of the guide 20 is interposed a spring 25 which normally holds the plunger 95 in raised position. The flat forward end of the bar 15 is disposed in substantial alignment, or in substantially the same vertical plane with the flat rear face of the plunger 21, only sufficient clearance being provided between said bar and plunger to 100 permit the latter to pass the former and to cooperate therewith to shear off the first staple of the strip when the plunger is depressed. The staple strip 19 is supported and slides on the top of the bar 15 with its 105 foremost staple normally projecting beyond the end of the bar in a position to be severed from the strip by the plunger 21 in its downward movement and to be driven through the throat 26 of the machine upon 110

the anvil 11, where it is clenched by the recess 12.

27 denotes a cam plate pivoted at 28 within the casing 13 at the rear of the 5 plunger 21. 29 denotes a feed pawl pivoted to the lower end of the cam plate 27 and held in engagement with the staple strip by a spring 30 interposed between said pawl and plate and seated in a socket in the lower 10 edge of the latter. 31 denotes a detent pawl pivoted at 32 to the casing and also held in engagement with the staple strip by a spring 33 carried by a stud 34. The cam plate 27 is oscillated on its pivot 28 at 15 each reciprocation of the plunger 21 by a lug 35 on said plunger which engages upper and lower cam surfaces 36 and 37 formed on said plate, said surfaces being so designed that at each oscillation of the cam 20 plate the feed pawl 29 will be moved through a distance corresponding to the width of one staple on the strip. When the plunger 21 is depressed, engagement of the lug 35 with the lower cam surface 37 causes 25 the feed pawl to be moved backwardly upon the strip, the detent pawl 31 at this time holding the strip against retrograde movement. When said plunger is raised, engagement of said lug with the upper cam 30 surface 36 causes said pawl to be moved forwardly to advance the strip. 38 denotes a plunger guided in a threaded thimble 39 which is seated in a threaded opening in the casing 13, said plunger being forced inwardly by a spring 40 interposed between the bottom of said thimble and a shoulder 35 formed on said plunger. The end of the plunger 38 is slotted to receive the rear edge of the cam plate 27 and acts to keep said 40 cam plate and the feed pawl 29 carried thereby normally in their forward position as well as to prevent lateral movement of said cam plate and thereby retain said feed pawl in proper alignment with the staple strip.

41 (Fig. 1) denotes channel members or slides located in the grooves 23 and embracing the ribs 22 on the plunger 21. The slides 41, while oppositely disposed, are substantially identical in form, and each comprises (see Figs. 4, 5, 6 and 7) a web 42 and front and rear flanges 43 and 44, the latter being provided with a notch 45 of substantially the same height as the several 50 staples of the strip 19 and adapted, when the slides are in one position, as hereinafter explained, to permit the entry into the slides of the foremost staple when the latter is fed into driving position beyond the end of the bar 15 and beneath the plunger 21. The rear flange 44 of each of said slides is also provided with a lug 46 having upper and lower shoulders which are engaged by upper and lower shoulders 47 (Fig. 1) and 48 (Fig. 8), respectively, on the plunger 21

when the latter is reciprocated, thereby moving the slides, said shoulders being vertically spaced to allow considerable lost motion between the plunger and slides. The webs 42 of the slides 41 have tongues 49 70 struck inwardly thereby to provide frictional means for holding said slides stationary in the grooves 23 when not positively moved by the plunger, said tongues bearing against the ribs 22 on the plunger 75 and acting to press the slides into said grooves. The upper ends of the slides 41 are split to form yielding tongues 50 which are sprung slightly outwardly and are provided with slightly rounded ends which are 80 received in the recesses 51 in the walls of the grooves 23 when said slides are in their lowermost position, thereby retaining said slides in this position.

The operation is as follows: When the 85 plunger 21 starts on its upward stroke, the slides 41 are in the position shown in Figs. 6 and 7, with the notches 45 in alignment with the staple strip 19, and as the plunger moves upwardly the feed pawl 29 advances 90 said strip to cause the foremost staple thereon to enter said slides through said notches. Just prior to the completion of the upward movement of the plunger 21, the shoulders 48 thereon engage the lugs 46 on the slides, 95 lifting said slides from the position shown in Fig. 6 into the position shown in Fig. 5, in which position the depending legs of the foremost staple are held between the flanges 43 and 44 below the slots 42. As the plunger descends, the foremost staple is cut from the end of the strip and, being held in upright position by engagement of the flanges 43 and 44 with its depending legs, is prevented from turning or bending. As the downward movement of the plunger continues, the shoulder 47 thereon engages the lugs 46 on the slides, causing them to move downwardly with the staple and insure its straight passage through the throat 100 105 110

26. Upon the completion of the downward movement of the plunger, the slides will have been returned to the position shown in Fig. 6 ready to receive another staple when the strip is again advanced upon the succeeding upward movement of the plunger.

In Fig. 9 is shown a modification of the staple holding and carrying slides, the slides 52, shown in said figure, being substantially L-shaped in cross section and comprising webs 53 and rear flanges 54 provided with lugs 55 and notches 56 corresponding substantially to the lugs 46 and notches 45 of the slides 41, the forward flanges 43 of the latter slides having been omitted inasmuch as the turning tendency of the staple is usually toward the rear. Also, the spring tongue 49 and spring fingers 50 have been omitted, the frictional engagement of the slides with the walls of the 115 120 125 130

guides being depended upon to hold said slides stationary when not positively moved. The operation of the slides 52 is substantially similar to that of the slides 41, as will be understood without further explanation.

Having thus described my invention, I claim:

1. In a strip staple machine, the combination with means for feeding a staple strip 10 and means for severing and driving the individual staples, of means for engaging a leg of the foremost staple on said strip and holding said staple against turning during the severing operation, said machine having 15 means for positively moving said engaging and holding means into and out of a position so to engage said leg.

2. In a strip staple machine, the combination with means for feeding a staple strip 20 and means for severing and driving the individual staples, of a member for engaging the foremost staple on said strip and holding the same against turning, and means operated by said severing and driving means for 25 actuating said member, said actuating means having a lost motion connection with said member to permit the latter to remain stationary during the feeding operation.

3. In a strip staple machine, the combination with means for feeding a staple strip 30 and means for severing and driving the individual staples, of a member for engaging the foremost staple on said strip and holding the same against turning, said member being operated by said severing and driving means to and from staple holding position and having a lost motion connection therewith to permit said member to remain stationary during the feeding operation, and 35 means for retaining said member in stationary position.

4. In a strip staple machine, the combination with a casing having recesses, means in said casing for feeding a staple strip, and 40 means for severing and driving the individual staples, of a member for engaging the foremost staple on said strip and holding the same against turning, said member being operated by said severing and driving means and having a lost motion connection therewith to permit said member to remain stationary during the feeding operation, and 45 said member being provided with spring arms adapted to engage said recesses to hold 50 said member in its stationary position.

5. In a strip staple machine, the combination with means for feeding a staple strip and a plunger for severing and driving the individual staples, of a member for engaging 60 the foremost staple on said strip and holding the same against turning, cooperating shoulders on said plunger and member whereby said member is operated by said plunger to and from staple holding position, said shoulders being spaced to pro-

vide lost motion between said plunger and member to permit said member to remain stationary during the feeding operation, and means for retaining said member in stationary position.

6. In a strip staple machine, the combination with a casing, means in said casing for feeding a staple strip, and a plunger for severing and driving the individual staples, of a member for engaging the foremost 75 staple on said strip and holding the same against turning, said member being operated by said plunger and having a lost motion connection therewith to permit said member to remain stationary during the 80 feeding operation, and said member having a spring tongue adapted to engage said plunger and force said member into holding engagement with said casing.

7. In a strip staple machine, the combination with means for feeding a staple strip and means for severing and driving the individual staples, of a channel member having side flanges to engage a leg of the foremost staple on said strip and hold said 90 staple against turning, one of said flanges having a notch to receive said staple, and said member being movable to carry said notch into and out of alinement with said strip.

8. In a strip staple machine, the combination with means for feeding a staple strip and means for severing and driving the individual staples, of a channel member having side flanges to engage a leg of the foremost staple on said strip and hold said staple against turning, one of said flanges having a notch to receive said staple, and means for positively moving said member to carry 100 said notch into and out of alinement with said strip.

9. In a strip staple machine, the combination with means for feeding a staple strip and a plunger for severing and driving the individual staples, of a channel member having side flanges to engage a leg of the foremost staple on said strip and hold said staple against turning, one of said flanges having a notch to receive said staple, and said member being moved by said plunger to carry 110 said notch into and out of alinement with said strip.

10. In a strip staple machine, the combination with means for feeding a staple strip and a plunger for severing and driving the individual staples, of a channel member, having side flanges to engage a leg of the foremost staple on said strip and hold said staple against turning, one of said flanges having a notch to receive said staple, and cooperating shoulders on said plunger and member for moving said member to carry 120 said notch into and out of alinement with said strip.

11. In a strip staple machine, the combi- 130

nation with means for feeding a staple strip, a plunger for severing and driving the individual staples, and guides for said plunger, of channel members in said guides having side flanges to engage the legs of the foremost staple on said strip and hold said staple against turning, one of the flanges of each of said members having a notch to receive said staple, and said members being movable in said guides to carry said notches into and out of alinement with said strip.

12. In a strip staple machine, the combination with means for feeding a staple strip and means for severing and driving the individual staples, of a channel member having side flanges to engage a leg of the foremost staple on said strip and hold said staple against turning, one of said flanges having a notch to receive said staple, said member being operated by said severing and driving means to carry said notch into and out of alinement with said strip and having a lost motion connection with said severing and driving means to permit said member to remain stationary during the feeding operation.

13. In a strip staple machine, the combination with means for feeding a staple strip and means for severing and driving the individual staples, of a channel member having side flanges to engage a leg of the foremost staple on said strip and hold said staple against turning, one of said flanges having a notch to receive said staple, said member being operated by said severing and driving means to carry said notch into and out of alinement with said strip and having a lost motion connection with said severing and driving means, and means for holding said member in stationary position with said notch in alinement with said strip during the feeding operation.

14. In a strip staple machine, the combi-

nation with means for feeding a staple strip and means for severing and driving the individual staples, of a member having means for engaging the foremost staple on said strip and holding the same against turning during the severing operation, said member being movable with said staple as it is driven to guide said staple and carry said engaging means out of the path of movement of said strip when it is fed.

15. In a strip staple machine, the combination with means for feeding a staple strip and a plunger for severing and driving the individual staples, of a channel member having a flange to engage a leg of the foremost staple on said strip and hold staple against turning, said flange having a notch to receive said staple, and means operatively connecting said channel member and plunger for causing said flange to engage said staple as it is severed, for moving said member with said staple as it is driven, and for causing said member to remain with said notch in alinement with said strip when the latter is advanced by said feeding means.

16. In a staple binder, a casing, means housed in said casing for feeding a staple strip therethrough, a plunger operative to reciprocate in said casing, said plunger being operative to sever individual staples from said strip and drive the same, and guide means for said individual staple operated by said plunger, said guide means being operative to cooperate with all four sides of said individual staple.

17. In a staple binder, a casing, a plunger for severing staples from a staple strip operatively supported by said casing, guide means for said staple, and said guide means being in the form of a sleeve that cooperates with the rear face, the two side faces, and the front face of said plunger.

In testimony whereof I affix my signature.
JOHN MUTH.
